DESIGN FOR A COMBINED CIGAR LIGHTER DISPLAY AND STAND

Alexander Sydney Weston, New York, N. Y.

Application March 6, 1940, Serial No. 90,730

Term of patent 7 years

To all whom it may concern:

Be it known that I, Alexander Sydney Weston, a citizen of the United States, residing at New York, in the county and State of New York, have invented a new, original, and ornamental Design for a Combined Cigar Lighter Display and Stand, of which the following is a specification, reference being had to the accompanying drawing, forming a part thereof.

In the drawing:

Fig. 1 is a front elevational view of a combined cigar lighter display and stand, showing my new design;

Fig. 2 is a top plan view thereof, and
Fig. 3 is a side elevational view.

I claim:

The ornamental design for a combined cigar lighter display and stand, as shown.

ALEXANDER SYDNEY WESTON.
